(57) **CLAIM**

The ornamental design for a clinical application system for the administration of drugs and feeds, as shown and described.

DESCRIPTION

FIG. 1 is a front elevation view of a clinical application system for the administration of drugs and feeds according to a first exemplary embodiment;

FIG. 2 is a bottom plan view thereof;

FIG. 3 is a top plan view thereof;

FIG. 4 is a left-side elevation view thereof, the right-side elevation view being a substantial mirror image thereof; and FIG. 5 is a front isometric view thereof.

FIG. 6 is a front elevation view of a clinical application system for the administration of drugs and feeds according to a second exemplary embodiment;

FIG. 7 is a bottom plan view thereof;

FIG. 8 is a top plan view thereof;

FIG. 9 is a left-side elevation view thereof, the right-side elevation view being a substantial mirror image thereof; and FIG. 10 is a front isometric view thereof.

FIG. 11 is a front elevation view of a clinical application system for the administration of drugs and feeds according to a third exemplary embodiment;

FIG. 12 is a bottom plan view thereof;

FIG. 13 is a top plan view thereof;

FIG. 14 is a left-side elevation view thereof, the right-side elevation view being a substantial mirror image thereof; and FIG. 15 is a front isometric view thereof.

FIG. 16 is a front elevation view of a clinical application system for the administration of drugs and feeds according to a fourth exemplary embodiment;

FIG. 17 is a bottom plan view thereof;

FIG. 18 is a top plan view thereof;

FIG. 19 is a left-side elevation view thereof, the right-side elevation view being a substantial mirror image thereof; and FIG. 20 is a front isometric view thereof.

FIG. 21 is a front elevation view of a clinical application system for the administration of drugs and feeds according to a fifth exemplary embodiment;

FIG. 22 is a bottom plan view thereof;

FIG. 23 is a top plan view thereof;

FIG. 24 is a left-side elevation view thereof, the right-side elevation view being a substantial mirror image thereof; and, FIG. 25 is a front isometric view thereof.

The broken line showing of the clinical application system for the administration of drugs and feeds is for the purpose

(Continued)

of illustrating portions of the clinical application system for the administration of drugs and feeds and forms no part of the claimed design.

The clinical application system for the administration of drugs and feeds is shown with a symbolic break in its length. The appearance of any portion of the article between the break lines forms no part of the claimed design.
